UNITED STATES PATENT OFFICE.

OTTO PEARSON, OF MOUNT JEWETT, PENNSYLVANIA.

SLED-BENCH.

1,183,227.

Specification of Letters Patent.

Patented May 16, 1916.

Application filed March 1, 1915. Serial No. 11,234.

To all whom it may concern:

Be it known that I, OTTO PEARSON, a subject of the King of Sweden, residing at Mount Jewett, in the county of McKean and State of Pennsylvania, have invented certain new and useful Improvements in Sled-Benches; and I do declare the following to be a full, clear, and exact description of the invention, such as will enable others skilled in the art to which it appertains to make and use the same.

This invention relates to improvements in sleds and more particularly to benches therefor.

15 One object of the invention is to provide a sled bench which is so constructed that the offset ends thereof will not crack or break and which relieves the runners of extraordinary strains.

20 Another object is to so construct a bench of this character which while cheap to manufacture will not buckle when subjected to jars from the side of the sled which occur when the sled skids sidewise.

25 Another object is to provide a light, strong and durable device of this character which is also cheap to manufacture.

With these and other objects in view the invention consists of certain novel features 30 of construction, and the combination and arrangement of parts as will be hereinafter more fully described and claimed.

In the accompanying drawings: Figure 1 is a side view of a sled equipped with this 35 improved bench; Fig. 2 is a bottom plan view of a portion thereof; Fig. 3 is a vertical transverse section taken on the line 3—3 of Fig. 1; Fig. 4 is a longitudinal section taken on the line 4—4 of Fig. 3; Fig. 5 is a 40 detail perspective view of the bench; Fig. 6 is a detail perspective view of one of the benches; Fig. 7 is a detail perspective view of the cross bar of the bench; Fig. 8 is a detail perspective view of one of the spacing 45 elements arranged between the cross bar and the knee; Fig. 9 is a plan view of the blank from which the knee is constructed; Fig. 10 is a detail longitudinal section of one 50 end of the bench showing a slightly different form of the invention; and, Fig. 11 is a detail perspective view thereof.

In the embodiment illustrated, a sled S is shown having the usual runners R which may be constructed of any suitable material 55 and of any desired cross sectional configuration. A top T is shown supported by the

runners R and connected therewith by benches 1 which constitute this invention. A steering bar A is shown connecting the top T with the cross bar B which connects the front ends of the runners to adapt the runners to be flexed for steering purposes but this construction is not necessary for sleds equipped with this invention as these benches may be employed in any form of sled.

The bench 1 which constitutes this invention comprises a cross bar 2 and knees 3 and 4 which are movably connected with said cross bar in a manner to be described. The 70 cross bar 2 is preferably constructed from a single piece of sheet metal which is bent to form a channel bar as shown in Fig. 7. The ends of this cross bar 2 are offset downwardly from the top of the beam to form 75 seats for the side bars of the sled frame, said offset ends being apertured to receive fastening elements for securing them to the side bars and also to the knees as will be hereinafter described. This cross bar 2 is 80 also provided with apertures 5 spaced inwardly from the apertures in the offset outer ends thereof for receiving fastening elements which connect the knees with the beam, and also the beam to the top. 85

The knees 3 and 4 which support the ends of the cross bar or beam 2 and connect it with the runners R are preferably constructed from the blank shown in Fig. 9 to adapt them to be made from small sheets of metal 90 thereby economizing in the construction of said knees. The blank from which each knee is constructed comprises a body portion 6 having diverging arms 7 which are bifurcated at their free ends to form attaching lugs 8 and said arms 7 are folded longitudinally to position said lugs opposite each other and adapt them to straddle the upstanding flange of the runner as shown in Figs. 3, 5, and 6 said lugs being apertured 95 as is also the flange of the runner to receive the fastening bolts or rivets which connect the free ends of the knee to the runner. The body portion 6 of the blank from which the knee is constructed is left unfolded to adapt it to fit flatly against spacing members 10 which are disposed in the channel bars 2 as will be hereinafter described. This body portion 6 between the arms 7 of the knee is provided with transversely aligned apertures 100 one of which is in the form of an arcuate slot 9 which is here shown arranged at the 105

- inner end of said body portion to provide for the movement of the knee relatively to the bench as will be described.
- A cross bar reinforcing member and knee bearing 10, is here shown disposed in the bar 2 at each end thereof and substantially fills said bar, with its outer face presenting a flat surface for receiving the flat body portion 6 of the knees 3 and 4. This member 10 which performs the double function of a reinforcing device for the cross bar and as a connecting and spacing means for the knee is preferably formed as shown in Fig. 8, the body portion 12 of which is substantially rectangular in form with side flanges 13 bent laterally inward and adapted to extend over and engage the edges of the flanges of the bar 2. A flange 14 is also formed at one end of the body 12 with the ends thereof spaced from the adjacent ends of the flanges 13 to provide for the reception between them of the side walls of the cross bar 2, said flange 14 being designed to fit between the flanges of the cross bar and being of a length slightly less than the distance between said cross bar flanges. The width of this flange 14 is substantially the same as the width of the flanges of the cross bar 2 at their outer ends so that after said member 10 is applied this flange 14 fits in the end of said cross bar and completely fills the space forming substantially a closure therefor and at the same time constituting a reinforcing and bracing member.
- A tongue 15 extends laterally from the other end of the body portion 12 of the member 10 and is of a width corresponding to the distance between the flanges of the cross bar to adapt it to fit in between said flanges when applied. This tongue is bent inwardly at right angles to the attached end thereof and extended parallel with the body 12 of the member 10 to provide a bracing plate 16 which may be of any desired length being herein shown about one-half the length of the body 12 of the device 10. The laterally extending spacing member 17 which connects the plate 16 with the body 12 is of a length corresponding to the width of the cross bar 2 at points beyond the offset ends thereof so that when the device is applied the plate 16 will engage the inner face of the connecting bar of the cross bar 2, the flange 14 and spacing member 17 preventing the flanges of the cross bar from being forced inwardly toward each other and the flanges 13 prevent them from being bowed outwardly. The plate 16 and the body portion 12 of the member 10 are provided with registering apertures 18 to receive fastening bolts 19 which pass through these apertures and through the aperture 5 in the cross bar 2. These bolts 19 also are designed to pass through the top T and through the arcuate slot 9 in the body portion 6 of the knee

which is mounted on this end of the cross bar, it being understood that one of these members 10 is arranged at each end of the cross bar and that a knee is supported thereby. A fastening element 20 preferably in the form of a bolt is extended through the aperture in the outer end of the body 6 of the knee and through an aperture 21 formed in the outer end of the body portion 12 of the spacing element 10 and extends through the aperture formed in the offset end of the cross bar 2 and through the adjacent side bar of the sled top. By this means the knees, spacing members 10, cross bars 2 and top T are connected, the arcuate slot 9 in the body portion of the knee permitting said knee to move laterally relatively to the cross bar and thus prevent the necessity of the runner with which said knee is connected from being bent, thereby relieving the runner of extraordinary strains.

From the above description it will be obvious that the cross bars, knees and spacing elements may be cut from strips of metal with practically no waste except for the holes and slots and yet when assembled forms a very strong, light and durable bench and that the members 10 which are disposed between the knees and the cross bar at opposite ends of the bench will prevent the cross bar from buckling and also prevent the bolts or rivets which hold the knees from a tendency to wobble.

In the form shown in Figs. 10 11 the bracing and connecting member 11 is constructed similarly to the member 11 of the other figures except that instead of having the flange 14 at the outer end thereof arranged as shown in the other figures, this flange is extended and offset inwardly, being of a width equal to the distance between the flanges of the cross bar and which is designed to engage the inner face of the offset end of said cross bar and lie between the flanges thereof thereby preventing the collapse of the flanges and forming a reinforce for the connecting bar thereof. This plate 14' is apertured to receive the bolt which passes through the aperture in the outer end of the cross bar 2 and through the side bar of the sled top. The remainder of this member 11 is the same in construction as the member 10 in the other figures.

I claim as my invention:

1. A sled bench comprising a cross bar composed of channel iron with the ends of the top thereof offset downwardly, reinforcing plates mounted in the ends of said bars and having side flanges overlapping the flanges of said bar and end flanges engaging the inner face of the top of said bar, and knees engaging said plates and pivotally connected therewith and to said bar.

2. A sled bench comprising a channel iron cross bar, reinforcing and spacing members

mounted in the ends of said bar and comprising substantially rectangular plates having side flanges overlapping the flanges of said bar, a flange at one end of said plate with its ends spaced from the side flanges thereof and extending in the same direction as said side flanges and adapted to fit between the flanges of the bar, a tongue extending inwardly from the other end of said 10 plate and parallel therewith, said tongue being spaced from said plate, and a knee mounted on said plate.

3. A sled bench comprising a channel iron cross bar, reinforcing and spacing members 15 mounted in the ends of said bar and comprising substantially rectangular plates having side flanges overlapping the flanges of

said bar, a flange at one end of said plate with its ends spaced from the side flanges thereof and extending in the same direction 20 as said side flanges and adapted to fit between the flanges of the bar, a flange at the other end of said plate with its ends spaced from the side flanges thereof, a tongue extending inwardly from the free end of said 25 flange and bearing on the inner face of the cross bar, and a knee mounted on said plate.

In testimony whereof I have hereunto set my hand in presence of two subscribing witnesses.

OTTO PEARSON.
